UNITED STATES PATENT OFFICE.

FRANK W. WOLFF, OF PARNASSUS, PENNSYLVANIA, ASSIGNOR TO UNION METAL PRODUCTS COMPANY, OF CHICAGO, ILLINOIS, A CORPORATION OF DELAWARE.

DEVICE FOR OPERATING CAR COUPLERS.

Application filed October 24, 1924. Serial No. 745,620.

This particular invention relates to what is generally known in the art as a rotating type of uncoupling device for car couplers and comprises an operating rod revolvably mounted on the car with brackets or in any other convenient manner, which rod is usually bent downwardly at the outer end to form a handle, and is bent outwardly at its inner end to form a crank projecting over the coupler, which crank is operatively connected to the coupler lock lifter. The standard vertical plane coupler has a knuckle pivoted to the coupler head and provided with a tail behind which the lock is placed. The lock lifter protrudes through and above the coupler head and is provided with a horizontally positioned eye. This lock lifter eye is $1\frac{1}{16}$ " in diameter and its axis is perpendicular to the longitudinal center of the car. This size and position has been determined by the American Railroad Association and is standard for the majority of couplers now in service.

My invention resides in the connection between the crank of the operating rod and the eye on the coupler lock lifter. When the handle is raised the rod is revolved and the crank is thereby raised which unlocks the coupler by raising the lock lifter.

The coupler moves backwardly and forwardly longitudinally of the car in buffing and draft and also moves sidewise in rounding curves, etc., and the connection between the coupler and the operating rod must permit such movements without the component parts becoming disengaged from each other or from either the coupler or the operating rod. It is frequently necessary to uncouple cars when they are coupled together and in contact so that it is impossible to throw the knuckle of either coupler. To meet this condition couplers are designed to assume a "lock set position" wherein the lock lifter can be raised from behind the tail of the knuckle and retained in such a position by means within the head of the coupler independent of the operating rod. This allows the operating rod to fall close to the lock lifter. To accommodate such a movement the connection between the operating rod crank and the coupler lock lifter has a vertically slid able connection or engagement with the crank arm. Formerly the rods had

a short chain connecting the crank arm to the lock lifter of the coupler which chains proved unsatisfactory and were responsible for a little more than half of the defects for uncoupling mechanisms reported by the Interstate Commerce Commission. These chains were defective because they were broken, missing, kinked and either too long or too short.

One of the objects of this invention is to provide a connection between the rod and the coupler which will eliminate the defects of the old chain and meet all service conditions required.

These short chains were broken by falling behind the coupler horn and being smashed between the coupler horn and the striking casting by impact of the cars in coupling. The device is designed so that the component parts cannot become disconnected from each other or from the operating rod or the coupler. The connection between the component parts and also their connections to the operating rod and the coupler are such that the device cannot become "kinked". Formerly when a brakeman wanted a small chain to repair one of the old connections he simply guessed as to the amount of chain required and applied it to the car, which accounts for the number of "too long" and "too short" chains reported by the commission. This is not possible with my device.

Another object is to provide a connection which may be hooked into the eye of the coupler lock lifter with the hooked members connected to the crank of the operating rod in a manner which permits it to adapt itself to the various service movements of the coupler but prevents it from becoming disengaged from the lock lifter in service.

Another object is to operatively connect the connector to the crank arm in such a manner that it retains the connector operatively connected to the coupler lock lifter.

Another object of the invention is to provide a device wherein the component parts are duplicates, therefore, interchangeable. Duplication, of course, also simplifies manufacture, handling, accounting, etc.

Another object is to obtain a device where in the component parts are duplicates so that they cannot be wrongfully applied to the car or to each other.

In the drawings:

Fig. 1 shows a portion of a railway car with my invention applied thereon.

Fig. 2 shows one of the component members of the device.

Fig. 3 shows a side view of Fig. 2.

Fig. 4 shows method of applying the device to the coupler.

Fig. 5 shows method of applying the device to the operating rod.

Fig. 6 shows a plan view of Fig. 5.

Fig. 7 shows the device assembled and applied to the car.

Fig. 8 shows a side elevation of Fig. 7.

Fig. 9 shows a top view of Fig. 7.

In a railway car the operating rod 1 is mounted on the end wall 2 by brackets 3 and has a handle 4 and a crank arm 5. The lock lifter 6 of the coupler 7 has a horizontally disposed eye 8. My invention resides in a connector for the lock lifter eye 8 to the crank 5 of the operating rod.

The connector comprises two preferably duplicate parts 10 shaped to have an open hook 11 at one end and a shank 12 at the other end. The upper end of the shank has a lip 14. The configuration is typically shown in Figs. 2 and 3 and is preferably stamped from a flat plate of steel, as shown in Fig. 3.

Two such members are positioned complementary together and pivotally secured to each other by rivet 16 (or other means). The device thus assembled is ready for shipment from point of manufacture and is also ready for application to the car.

To apply the device to the car it is opened up scissor fashion, as shown in Fig. 4, and the lower hooks 11 inserted through the eye 8 of the lock lifter 6 and then moved opposite each other to form a closed eye, as shown in Fig. 5. The connector is then inserted through the eye 17 of the operating rod crank arm, as shown in Fig. 6, and the rod is then rotated about ninety degrees until the relative position of the crank arm 5 and connector is as shown in Figs. 7, 8 and 9, when the application is complete. The width 18 of the crank arm eye 17 is only a little greater than the width 19 of the shank (and less than the width 20 in Fig. 5) and it will be noted that the attachment to the lock lifter eye 8 will not permit the connector to rotate about its vertical axis. The members are, therefore, operatively connected to the operating rod in such a manner as to retain them in the position of a closed eye.

The members are provided with shoulders which limit the downward and upward movement of the operating rod relative to the connector. The upper lips or shoulders 14 provide a means to raise the connector when the crank arm is raised. Numerous arrangements would perform this function; there-

fore, in my claims, I simply specify that the members are operatively connected to the operating rod. The lower shoulders 22 restrict the downward movement of the crank arm so that it cannot reach such a position that would permit the members to open up, as shown in Fig. 4, and allow the hooks to become disengaged from the lock lifter eye.

I claim:

1. A connector for a railway car coupler and its operating rod, said connector comprising a pair of complementary members pivotally connected together to move into alignment with each other to form a closed eye at one end and to simultaneously form a shank at the other end.

2. A connector for a railway car coupler and its operating rod, said connector comprising a pair of duplicate complementary members pivotally connected together to move into alignment with each other to form a closed eye at one end and to simultaneously form a shank at the other end.

3. In a device for operating a car coupler, the combination of an operating rod, a coupler lock lifter having an eye, and a connector comprising a pair of complementary members pivotally connected together to move into alignment with each other to form a closed eye which eye engages the eye of the lock lifter, said members operatively connected to said operating rod so as to retain them in the position of a closed eye.

4. In a device for operating a car coupler, the combination of an operating rod, a coupler lock lifter having an eye, and a connector, said connector comprising a pair of members pivotally connected together to move into alignment with each other to form a closed eye at one end which eye engages said lock lifter eye, and to simultaneously form a shank at the other end, said shank slidably and operatively connected to said operating rod so as to retain them in the position of a closed eye.

5. In a device for operating a car coupler, the combination of an operating rod, a coupler lock lifter, and a connector, said connector comprising a pair of members pivotally connected together to move into alignment with each other to form a shank, which shank slidably and operatively engages said operating rod, said connector operatively connected to said lock lifter.

6. In a device for operating a car coupler, the combination of an operating rod, a coupler lock lifter, and a connector therebetween, said connector comprising a pair of members connected together to form a shank, which shank slidably and operatively engages said operating rod, said members formed so as to limit the vertical movement of the operating rod relative to the connector in either direction.

7. In a device for operating a car coupler,

the combination of an operating rod, a coupler lock lifter having an eye, and a connector comprising a pair of complementary members connected together to form a closed eye, which eye engages the eye of the lock lifter, said members operatively connected to said operating rod so as to retain them in the position of a closed eye.

8. In a device for operating a car coupler, the combination of an operating rod, a coupler lock lifter, and a connector therebetween, said connector comprising a pair of members connected together to form a shank, which shank slidably and operatively engages said operating rod, said connector operatively connected to said lock lifter.

9. In a device for operating a car coupler, the combination of an operating rod, a coupler lock lifter having an eye, and a connector, said connector comprising a pair of members connected together to form a closed eye at one end, which eye engages said lock lifter eye and to simultaneously form a shank at the other end, said shank slidably and operatively connected to said operating rod so as to retain them in the position of a closed eye.

10. A connector for a railway car coupler and its operating rod, said connector com-

prising a pair of complementary members connected together to form a closed eye at one end and to simultaneously form a shank at the other end.

11. A connector for a railway car coupler and its operating rod, said connector comprising a pair of complementary members connected together to form a closed eye at one end and to simultaneously form a shank at the other end, each of said members having a shoulder at the base of the shank.

12. A connector for a railway car coupler and its operating rod, said connector comprising a pair of complementary members connected together to form a closed eye at one end and to simultaneously form a shank at the other end, each of said members having a shoulder at the base of the shank and a lip at the extremity thereof.

13. In a device for operating a car coupler, the combination of an operating rod, a coupler lock lifter, and a connector therebetween, said connector comprising a pair of members connected together to form a shank, which shank slidably and operatively engages said operating rod, said members formed so as to limit the upward vertical movement of the operating rod relative to the connector.

FRANK W. WOLFF.
